UNITED STATES PATENT OFFICE.

JOHN REEL, OF FRENCH CAMP, MISSISSIPPI.

DESIGN FOR A VIOLIN OR BANJO BRIDGE.

SPECIFICATION forming part of Design No. 28,956, dated June 28, 1898.

Application filed May 18, 1898. Serial No. 681,087. Term of patent 14 years.

To all whom it may concern:

Be it known that I, JOHN REEL, a citizen of the United States, residing at French Camp, in the county of Choctaw and State of Mississippi, have invented and produced a certain new and original Design for Violin or Banjo Bridges; and I do declare the following to be a full, clear, and exact description of the invention, such as will enable others skilled in the art to which it appertains to make and use the same.

My invention has relation to a new and original design for violin or banjo bridges; and it consists of a configuration and ornamentation shown in the accompanying drawings, in which—

Figure 1 is a perspective view of the bridge, and Fig. 2 is a front elevation.

The leading feature of my design comprises

a body portion 1, having a curved upper edge 2, diverging side edges 3, and a straight lower edge 4, formed with a V-shaped slot 5.

6 denotes arches projecting downwardly from the lower corners of the body portion and having ogee curves 8.

9 denotes holes in the body portion arranged in triangular fashion, and 10 denotes slits leading from two of the holes.

What I claim is—

The design for a violin or banjo bridge as herein shown and described.

In testimony whereof I have hereunto set my hand in presence of two subscribing witnesses.

JOHN REEL.
